Atty.

UNITED STATES PATENT OFFICE.

JOHN S. HURLEY, OF LYNN, MASSACHUSETTS, ASSIGNOR TO MICHAEL HURLEY, OF SAME PLACE.

THILL-TUG.

SPECIFICATION forming part of Letters Patent No. 449,906, dated April 7, 1891.

Application filed June 27, 1890. Serial No. 356,937. (No model.)

To all whom it may concern:

Be it known that I, JOHN S. HURLEY, of Lynn, in the county of Essex and State of Massachusetts, have invented certain new and useful Improvements in Thill-Tugs, of which the following is a specification.

This invention is an improvement upon the construction shown in Letters Patent granted to John S. Hurley, the present applicant, and Eugene H. Taylor; July 1, 1890, No. 431,467; and it consists in the details of construction hereinafter described and claimed.

In the accompanying drawings, forming a part of this specification, Figure 1 represents a side elevation of a thill-tug provided with my improvements. Fig. 2 represents an edge view of the same. Fig. 3 represents a section on line 3-3 of Fig. 1.

The same letters of reference indicate the same parts in all the figures.

In the drawings, *a* represents the hook-shaped body or main section of the thill-tug, the same being made of a suitable metal and comprising one side and the bottom portion 25 of the tug, its lower portion being formed to receive and support the thill.

b represents the hinged section, which is connected at its upper end by a hinge pintle or pivot *c* to the section *a*, the said sections 30 having hinge-ears *d* and *d'* formed on their upper ends, through which the pin passes, the ears of one section alternating with those of the other section. The hinged section *b* is formed to extend across the open side of the 35 section *a* and to bear at its swinging end on the corresponding end of said section *a*, as shown in Figs. 2 and 3, the arrangement being such that the section *b* swings outwardly to open the tug for insertion of the thill and 40 inwardly to close the tug after the thill is in place.

e represents a locking-lever, which is connected by a pivot-pin *e'* to ears *i* on the hinged section *b*, said ears being at or near 45 the swinging end of said section. The lever projects downwardly beyond the end of the section *b*, and is provided with a tongue *e''*, which projects inwardly and is adapted to enter a slot *g*, formed for its reception in the 50 section *a*, near the end of the latter, on which the hinged section bears.

The construction above described is substantially identical with that shown in the patent above referred to, and in said patent is also shown a spring *h*, composed of a strip 55 of metal attached at one end to the upper portion of the hinged section *b*, and bearing at its lower portion against the upper end of the locking-lever *e*, said spring being exposed upon the outer side of the tug, and therefore 60 liable to be bent or broken by contact with external objects.

In carrying out the present invention, I substitute for the spring shown in the above-mentioned patent a spiral spring *h'*, which is inserted in a recess or cavity *k*, formed in the hinged section *b*, and is arranged to press upon the upper portion of the locking-lever *e*, through the medium of a bolt or stud *m'*, fitted to slide in the socket *k*, and is pressed by the 70 spring *h'* against the tug *e'*, formed on the locking-lever *e*, above the pivot *e'* thereof. The portion of the hinged section *b* that constitutes the outer side of the socket *k* and covers the spring *h'* and stud *m'* is extended 75 downwardly to form a hood *n*, covering the upper portion of the locking-lever and the lug *e'* thereon and preventing the entrance of rain, dirt, &c., into the crevice at the upper end of the locking-lever and into the socket *k*. 80

It will be seen from the foregoing that by inclosing the spring *h'* in a socket arranged as shown in Fig. 3, said spring is entirely protected, so that it cannot be bent or broken by contact with external objects, and that the 85 employment of the hood *n* prevents said spring from being clogged by ice or accumulations of dust and dirt.

I have further improved the construction of the tug by forming a concave recess *p* in the body portion *a* of the tug, said recess being under the slot *g*, and arranged to permit the insertion of a thumb or finger under the lower end of the locking-lever for the purpose of forcing the latter outwardly to release the 95 hinged section. It will be seen that by the provision of the recess *p* I am enabled to form the locking-lever so that its lower end does not project outwardly from the outer side of the tug to such an extent as in the Hurley and Taylor patent above referred to, so that the 100 said locking-lever is less liable to be caught

and pulled outwardly by accidental means than heretofore. If desired, the spiral spring h' may be extended so as to bear directly on the tug e' , the sliding stud m' being omitted.

5 m represents a buckle, which is connected to the upper end of the main section a .

I claim—

1. The improved thill-tug composed of the main section a and the section b , hinged at its upper end to the section a and provided at its lower end with the downwardly-projecting pivoted locking-lever e , adapted to engage a slot in the main section and with the socket k , the spring h' , inclosed in said socket to exert pressure on the locking-lever, and the downwardly-projecting hood n , arranged to cover the mouth of the socket k and the upper end of the locking-lever, whereby the access of dirt, &c., into said socket is prevented,
- 15 as set forth.
- 20

2. The improved thill-tug composed of the main section a , having the recess p , and the hinged section b , provided at its swinging end with the locking-lever having a tongue adapted to engage said main section, the lower end of the said lever projecting below said tongue and being arranged adjacent to the recess p , so that space is afforded by said recess behind the lower end of the locking-lever for the insertion of a thumb or finger, as set forth. 25

In testimony whereof I have signed my name to this specification, in the presence of two subscribing witnesses, this 26th day of June, A. D. 1890. 30

JOHN S. HURLEY.
